Primary Examiner — Kevin K Rudzinski*Assistant Examiner* — James P McKane(74) *Attorney, Agent, or Firm* — Nicholas Martin; Greenberg Traurig, LLP(57) **CLAIM**

The ornamental design for a hat with a panel, as shown and described.

DESCRIPTION

FIG. 1 is a front perspective view of a hat with a panel showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The line shading on the hat bill, body panels of the hat, back strap, and the panel depict curved surfaces. The broken lines shown in the drawings depict portions of the article that form no part of the claimed design.
